UNITED STATES PATENT OFFICE.

FREDERICK JOHN GAY, OF CAMBERWELL, ENGLAND.

SEAT, CHAIR, BUNK, AND THE LIKE.

1,073,415.

Specification of Letters Patent. Patented Sept. 16, 1913.

Application filed November 2, 1912. Serial No. 729,183.

To all whom it may concern:

Be it known that I, FREDERICK JOHN GAY, a subject of His Majesty the King of England, residing at 83 Grove Lane, Camberwell, in the county of London, Kingdom of England, have invented certain new and useful Improvements in Seats, Chairs, Bunks, and the Like, of which the following is a specification.

10 This invention relates to improvements in seats, chairs, bunks, cattle stalls, and the like in which it is possible for the occupant to remain in a horizontal position during the rolling or pitching of a ship upon 15 which the device is to be used.

It refers more particularly to devices of the kind in which the seat, chair, bunk, or the like is hung in a pivoted frame forming part of a gimbal mounting.

20 My present invention is clearly described with reference to the accompanying drawings in which:

Figure 1 is a perspective view of a seat or chair showing the hooks by which it is suspended; Fig. 2 is a perspective view of the swinging frame hereinafter referred to; Fig. 3 is a perspective view showing a base frame to which a pair of uprights are pivotally mounted and provided with 25 means for retaining them in a vertical position; Fig. 4 shows the chair, frame and base mounted together as in use; Fig. 5 shows the whole device folded up ready for storage; Fig. 6 is a perspective view showing 30 my invention applied to a boat in which a plurality of bunks or beds are mounted one above another; and Fig. 7 is a perspective view of a veil or curtain intended to prevent the occupant of the chair or 35 bunk from observing relative movements of the ship or the like.

As shown and in carrying out my invention, the seat, chair, bunk, stall, or the like, which may be of any suitable construction, is provided with suspending hooks A at opposite sides which are adapted to engage with corresponding suspending hooks on the upper ends of a swinging frame B. The swinging frame B 40 comprising a U shaped member having cross bars at the upper ends of its free arms, and these cross bars are formed into hooks at each of their outer ends so that the near side hook on one arm and the far side hook on the other arm are formed for 45 engaging with the hooks on the chair or

the like. The remaining more or less diagonally disposed hooks are suitably formed for engaging with other hooks provided at the upper end of a pair of vertical stanchions C, which latter are pivotally mounted upon a rectangular frame D and are provided with means whereby they may be retained in their vertical position. These uprights are also as shown in Fig. 60 3 more or less diagonally arranged. By this means although the frame D is free to rock in unison with the motion of the ship, the chair or the like will remain by the weight of the occupant in a horizontal 65 position owing to the interposition of the U shaped frame B. Obviously instead of providing hook shaped joints for connecting the parts together, I may also provide ball and socket or other forms of universal 70 joints at these parts.

As shown, a spring E is attached at the base, D, and connected to a sliding member, F, mounted on a cord or wire, G; this cord is suitably fastened to act as safety 80 brake. Cords or straps E' and the like are placed by side of springs for purpose of greater safety. Pads, H, are fitted to the base of chair frame D and on the bottom of the stanchions C to prevent communication of any vibration from ship. Transverse members Q may be fitted to base 85 as shown in Fig. 4 to keep stanchions firm when chair is in use and prevent them from folding laterally.

The construction of the chair enables the extension of seat or leg rest, J, which is hinged to the seat K, and which is upholstered on both sides, to be folded back over the said seat, K, to form an armchair. 90 The back, L, also folds down over the seat K and leg rest J for convenience of stowing away when the chair is not required for use. The back is supported by stays, M, after the manner shown in Fig. 1, N, being 95 the sockets in which the stays fit. When the leg rest J, is unfolded, bolts O, are shot into sockets O'.

Fig. 6 shows a convenient method of suspending a plurality of beds in ships' cabins 100 from pairs of stanchions which are fixed to the floor and ceiling. In this case the swinging frame is attached to the stanchions after the manner previously described and shown and the bunk is as before hung 110 by hooks or the like from the swinging frame.

Fig. 3 indicates in dotted lines the manner in which the uprights or stanchions for supporting the swinging frame may be folded down for packing or transit.

5 In Fig. 7 of the drawings is illustrated a yoke member which may be attached through the depending rods P' , and the sockets P upon the rear of the back member L to project forwardly therefrom, and
10 curtains may be arranged upon the forwardly extending portion to obscure from the view of the occupant any vision of the water or movements of the ship.

What I claim as my invention and desire
15 to secure by Letters Patent of the United States is:—

1. A device of the kind described for use on board ship comprising in combination a base carrying a pair of upright or stanchions, a swinging frame having four more or less rectangularly disposed hooks or members thereon and adapted to engage by means of two diagonally opposite hooks or members with the said stanchions, and a
25 chair or the like suspended from the other of said hooks or members so as to be free to remain horizontal irrespective of the inclination of the vessel.

2. A device of the kind described for use
30 on board ship comprising in combination a base carrying a pair of uprights or stanchions pivotally connected therewith, a U

shaped swinging frame having four more or less rectangularly disposed hooks or members thereon at its ends and adapted to engage 35 by means of two diagonally opposite hooks or members with the said stanchions, and a chair or the like suspended from the other pair of said hooks or members so as to be free to remain horizontal irrespective of the 40 inclination of the vessel.

3. A device of the kind described for use on board ship comprising in combination a base carrying a pair of uprights or stanchions pivotally connected therewith, means 45 for securing said stanchions in a vertical position, a U shaped swinging frame having four more or less rectangularly disposed hooks or members thereon at its ends and adapted to engage by means of two diagonally 50 opposite hooks or members with the said stanchions, and a chair or the like suspended from the other pair of said hooks or members so as to be free to remain horizontal irrespective of the 55 inclination of the vessel.

In testimony whereof I have hereunto signed this specification this 23rd day of October 1912.

FREDERICK JOHN GAY.
